UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

GARMENT POCKET.

Application filed August 20, 1919. Serial No. 318,702.

To all whom it may concern:

Be it known that I, JAMES R. MOFFATT, a citizen of the United States, residing at Chicago, in the county of Cook, State of Illinois, have invented certain new and useful Improvements in Garment Pockets, of which the following is a description, reference being had to the accompanying drawing and to the figures of reference marked 10 thereon.

The invention relates to new and useful improvements in garment pockets, and more particularly to the seam for uniting the edges of the fabric sections forming the 15 pocket.

An object of the invention is to form a garment pocket wherein the edge portions of the fabric sections are firmly secured by stitches, and the edges thereof covered by 20 covering stitches, the securing stitches and covering stitches being independent of each other and the securing stitches so disposed as to protect the covering stitches from strain incident to the contents of the pocket.

In the drawings, which show by way of illustration one embodiment of the invention:—

Figure 1 is a front view of a section of a garment showing a portion of a pocket having a seam made in accordance with the 30 invention.

Fig. 2 is a rear view of the same;

Fig. 3 is a sectional view on the line $x-x$ of Fig. 1;

Fig. 4 is a sectional view on the line $y-y$ of Fig. 1;

Fig. 5 is an enlarged plan view of a portion of the seam for uniting the edges of the fabric;

Fig. 6 is a bottom plan view of the same; and

Fig. 7 is a view showing, more or less diagrammatically and on an enlarged scale, a section on the line $z-z$ of Figure 6.

The invention consists broadly in a garment pocket wherein the fabric sections forming the same are joined adjacent their edges by means of a line of stitches such as double-locked stitches, wherein the edges 50 outside of the joining line of stitches are secured and covered by covering stitches. The line of double-locked stitches is independent of the covering stitches and receives the strain incident to the articles car-

ried in the pocket. The covering stitches 55 are disposed wholly outside of the double-locked stitches and are therefore protected by said double-locked stitches.

In the drawings I have shown a garment 60 pocket embodying the improvements.

A section of a garment is indicated at 1. The pocket opening 2 is formed in the usual manner. The inner face of the garment at the pocket opening is provided with a facing strip 3. The pocket is preferably formed 65 of a fabric section, indicated at 4, which is folded at 5, so as to form an inner section 6 and an outer section 7. The edge of the inner section 6 passes beneath the facing strip 3 along side of the pocket opening 2. Also along side of the pocket opening 2 is a facing strip 8. The edges of the sections 6 and 7, except at the pocket opening, are joined by a line of double-locked 70 stitches 9.

As shown in Figure 7 of the drawings, these stitches 9 are in the form of double-locked stitches and are made from a needle thread 10 which is formed into loops 11 which are locked by means of a looper 75 thread 12 formed into locking loops 13. This double-locked stitch is of the usual character; it is a non-raveling stitch. This stitching is placed back from the inner and outer edges 6 and 7 and substantially parallel therewith.

Located wholly outside of the line of double-locked stitches are covering stitches 14 which consists of needle threads 15 and 16 formed into a series of loops which are 80 joined and locked by a looper thread 17. On the upper face of the fabric the needle thread loops are joined by a cross thread 18. These threads form covering stitches which 85 completely cover and protect the edges of the sections of the fabric. The double-locked stitches are spaced from and parallel with the covering stitches.

As above noted, the line of double-locked stitches lies inside of the covering stitches, and, therefore, the strain due to heavy articles placed in the pocket comes directly upon the line of double-locked stitches which is not liable to break and, if it does break, will not ravel. This line of stitches 100 protects the covering stitches so that no strain whatever comes upon the covering 105 stitches.

At the pocket opening 2, the edges of the inner and outer sections are, of course, not joined, but the covering stitches and also the line of double-locked stitches will pass along the edge of the inner fabric section 7, as clearly shown in Figure 3 of the drawings.

I am aware that it is not new with me to combine a straight line of stitching and an overseaming stitching, as such is shown and described in the patent to Fefel, No. 407,286, granted July 16, 1889, and I do not claim such combination broadly. In this patent, however, the straight line of stitching is within and enclosed by the overseaming stitches, and, therefore, in such a seam the strain will come first upon the overseaming stitches, which would be likely to break, thus releasing the covering threads and making the seam unsightly. By my improved seam, however, the overedge or covering stitches are completely protected by the line of double-locked stitches and no strain whatever comes on the covering or

overedge stitches which would likely rupture and cause the seam to ravel. 25

It is obvious that minor changes in the details of construction may be made without departing from the spirit of the invention as set forth in the appended claim. 30

Having thus described the invention, what I claim as new and desire to secure by Letters Patent, is:

A garment pocket comprising inner and outer fabric portions shaped to form a pocket, the free edges of said inner and outer portions being independently joined to the garment at the pocket opening, said free edges being united throughout the remainder of their extent by covering stitches 35 and a line of double locked stitches disposed at a greater distance from the edges of the fabric portions than the innermost part of the covering stitches and substantially parallel therewith. 40

In testimony whereof, I affix my signature.

JAMES R. MOFFATT.
